CLAIM

The ornamental design for a lipstick case, as shown and described.

DESCRIPTION

FIG. 1 is a front elevational view of a lipstick case showing my new design, the side opposite being identical to the side shown;

FIG. 2 is a side elevational view thereof, the side opposite being identical to the side shown;

FIG. 3 is a top plan view thereof;

FIG. 4 is a bottom plan view thereof; and,

FIG. 5 is an exploded perspective view thereof.

The partially disclosed lipstick element in FIG. 5 is understood to have a conventional shape.

FIG. 3

FIG. 4
